Fig. 3.

Fig. 4.

Fig. 5.

Fig. 6.

Fig. 7

FIG. 1 is a top plan view of a combined carrying and storage case showing my new design;

FIG. 2 is a front elevational view thereof;

FIG. 3 is an end elevational view thereof;

FIG. 4 is a bottom plan view thereof;

FIG. 5 is a rear elevational view thereof;

FIG. 6 is a front elevational view of an embodiment of my new design wherein a handle is recessed in the lower front face panel; and

FIG. 7 is an end elevational view of the combined carrying and storage case of FIG. 6.

The ends not shown in FIGS. 3 and 7 are mirror images of the respective ends shown therein.

The container of FIGURE 6 looks the same in rear elevation as the container shown in FIGURE 5, except for those differences which are apparent from the drawing.

The container of FIGURE 6 looks the same in top

and bottom plan as the container of FIGURES 1 and 4, respectfully, except for those differences which are apparent from the drawing.

I claim:

The ornamental design for a combined carrying and storage case, substantially as shown and described.
